George A. Forman
Attorney

UNITED STATES PATENT OFFICE.

JAMES W. KENNEDY, OF CANTON, OHIO.

SIGNALING APPARATUS.

Application filed October 2, 1922. Serial No. 591,802.

To all whom it may concern:

Be it known that I, JAMES W. KENNEDY, a citizen of the United States, residing at Canton, in the county of Stark and State of Ohio, have invented certain new and useful Improvements in Signaling Apparatus; and I do hereby declare the following to be a full, clear, and exact description of the invention, such as will enable others skilled in the art to which it appertains to make and use the same.

My invention consists of certain novel and useful improvements in railway signaling apparatus, and relates more particularly to that class of signaling apparatus set forth in my United States Patent No. 1,421,252. My present invention comprises certain improvements in the structure set forth in my said patent as will be fully disclosed in the specification following, reference being had to the accompanying drawings in which my invention is illustrated, and being more particularly pointed out in the appended claims.

I have illustrated my present invention as applied more particularly to side tracks entering a main line, but it is to be understood that my improvements may be used on the main line itself, for backing up trains or switching cars on the main line.

In the construction disclosed in my former patent, the signaling apparatus is operated by the engine, so that in the backing up of a long train, it may happen that the rear cars pass a crossing without setting the signal, and that the signal will not be set until the engine reaches the signal operating devices.

One of the objects of my present invention is to overcome this fault, and to provide a mechanism wherein the warning signal will be set at once by the rear car of a backwardly moving train, and the crossing will be immediately marked "Clear" if for any reason the direction of the train is changed to a forward movement.

In the drawings:

Fig. 1 is a perspective view of a crossing provided with my improved safety appliances.

Fig. 2 is a plan view of a main rail road track with a side track entering it, provided with my improved signal operating devices.

Fig. 3 is a side view of a rail and signal operating devices.

Figs. 4 and 5 are detail views of parts of said construction.

Fig. 6 is a side view showing signal operating rods and wires.

Fig. 7 is a detail view on line α — α of Fig. 3.

Fig. 8 is a fragmentary plan view, showing the trip with resilient extension.

Similar numerals indicate identical parts throughout.

1 represents the main line of a railroad track broken away as in Figs. 1 and 2, showing that there is practically no limit to the distance apart the operating mechanisms may be placed.

2 represents a crossing and 3 a signaling device, all as set forth in my previous patent above referred to.

4 represents a side track entering the main line, and is provided with means for operating the signaling devices which I will now describe.

5 represents the inside of a rail shown in Fig. 2. This rail is provided with a shoe made in three parts as shown in Fig. 4 and comprises a plate 6 adapted to pass beneath the rail and being bent over the flange of the rail as at 7, to which it is clamped by a stud bolt 8 or other desired means.

Secured to the plate 6 by suitable bolts 9 is a part 10 which engages the upper surface of the flange of the rail and is provided with two ears 11 between which a part 12 is pivoted, the said part 12 being provided with a recess in which is pivotally mounted a longitudinally extending ramp 13.

The part 12 is also provided with a pin 14 adapted to engage one end of a spiral spring 14', the other end of which engages a similar pin 16 projecting from a part 17 bolted to the plate 6, for a purpose hereinafter described.

The ramp 13 consists of a rigid part 13' having a vertical flat face adapted to normally lie adjacent to the web of the rail and having its upper surface slightly concave as shown in Fig. 3, terminating in a longitudinally extending knife edge, merging with the inner face of the head of the rail, for a purpose hereinafter described. The ramp 13 is provided with a resilient part 13² firmly secured to said rigid part as at 13³. To the outer end of the resilient part 13² is secured

a plate 18 having an oval surface adapted to slide upon the face of a shoe 19 for a purpose hereinafter set forth. The other end of the ramp 13 is curved as at 13⁴.

5 The shoe 19 is made in two parts as shown in Fig. 7 and comprises a plate 20 adapted to pass beneath the rail and to be bent over the flange of the rail as at 21, and secured in place by a stud bolt 22. The other portion 10 23 of the shoe is formed to fit the web of the rail and the inner part of the rail as shown in Fig. 7 and is bolted to the base 20.

15 24 represents one of the uprights upon which a disk 25 is rotatably mounted, for operating the wires 26 setting and releasing the warning signals. The wires 26 are preferably additionally supported upon a wire 27, by means of depending cords or wires 28, which prevent the operating wires 26 from 20 sagging or breaking under the weight of ice or snow.

25 The wires 26 are attached to tension springs 26' which in turn are secured to lugs 29 on the disk. Pivotaly mounted on lugs 30 on the disk 25, are vertically disposed rods 31 provided intermediate their ends with turn buckles 32, said rods being pivotaly secured at their lower extremities to a cross arm 33, rigidly secured to the end of the 30 transverse operating rod 34, which is loosely mounted in a socket provided in the upright 24.

35 It will be noted that there are a number of openings 35 provided in the cross arm 33, through which the rods 32 may be pivotaly mounted on the cross arm, to permit the leverage to be varied so that more than a certain weight will be required to operate the signal, thus preventing tampering with said signal. It is of course obvious that the disks 25 must be similarly provided with a plurality of apertures through which the upright rods 31 are secured to said disk.

40 45 It will also be noted, that for operating the signal either to indicate danger, or a clear track the operating disk 25 is rotated always by the downward pull of one of the rods 31.

50 55 The transverse rod 34 is connected to the actuating rod 36 by a universal joint 37. The rod 26 at a portion of its length is provided with a laterally projecting plate 38 (see Fig. 5) adapted to be loosely engaged by a lug 39, depending from the under side of the ramp 13. I prefer to provide the lower face of the lug 39 with suitable roller bearings to prevent undue friction between said lug and the plate 38.

60 65 From the above, the operation of my device is thought to be obvious. Assuming that a train is entering the side track 4 as in Figs. 2 and 3 from left to right, in which position the ramp 13 is down below the bearing surface of the wheel, the flange of the wheel 40 passes between the ramp 13 and the

rail, and tips the said ramp to one side on the pivot 11 sliding the lug 39 on the plate 38, and leaving the signaling devices unaffected.

70 This action is made possible by the combined rigid and resilient parts of the ramp 13, which permit the ramp 13 to be moved entirely away from the rail.

75 As the train continues to move, the wheels pass over the resilient portion of a second ramp 41 corresponding to ramp 13 and when it reaches the rigid portion of said ramp the flange takes over the knife edge of the said part, hugs it to the rail and depresses said ramp 41 on its pivot, forces the part 38 80 downwardly upon the part 39 and rotates the actuating rod 36 connected by a universal joint 37 to the transverse rod 34 connected to the signaling devices and sets the latter.

85 It will be noted that the coiled springs 14' tend to maintain the ramps 13 and 41 in position against the rail returning them to that position after the wheels have passed.

90 It will also be noted that after the wheels have passed the fulcrum of the ramp, 41, as the forward portion of the said ramp descends, the part 42 will actuate the rod 43 shown in dotted lines in Fig. 3, which operating the part 44 rotates the rod 45, raising the part 38 against the part 39 and thereby setting the ramp 13 in operative position, for a train moving from right to left, it being a fact that the operation of the ramp 41 as described sets the warning signal for danger, 100 and the reverse movement of the train actuating the ramp 13, sets the signal showing the track to be clear.

105 It should be stated that the tension springs 26' serve a double purpose, in that they keep the wires taut without danger of breakage in hot or cold weather, and the other is that if on a main line one train is setting a signal for danger, and another train moving in the opposite direction is setting the signal at 110 safety, the springs compensate for the pull in opposite directions and prevent breakage.

What I claim and desire to secure by Letters Patent is:—

115 1. Apparatus for operating a permanently located semaphore, comprising a longitudinally extending ramp pivotally mounted upon a pivotally mounted support, an actuating rod, a supplemental rod operatively connected with the actuating rod for operating the semaphore and means provided on the longitudinally extending ramp for rotating the actuating rod.

120 125 2. Apparatus for operating a permanently located semaphore, comprising a pair of longitudinally extending ramps pivotally mounted upon pivotally mounted supports, an actuating rod, supplemental rods connected to the actuating rods for operating the semaphore, means provided on the lon- 130

itudinally extending ramps for rotating the actuating rods and a connection between the actuating rods, whereby the signals on the semaphore are alternately set to indicate 5 danger or safety, by a moving train.

3. Apparatus as claimed in claim 1 in which the connection between the actuating rod and the supplemental rod consists of a universal joint.

10 4. Apparatus as claimed in claim 1, in which the longitudinally extending ramp is composed of rigid and resilient parts.

5. Apparatus as claimed in claim 1 in which the longitudinally extending ramp is 15 composed of rigid and resilient parts, the rigid part being curved at one end and provided with a concave upper face.

6. Apparatus as claimed in claim 1 in which the support for the longitudinally extending ramp consists of a shoe comprising 20 a base plate, a part rigidly secured to said base plate and fitting over the flange of the rail, said part being provided with a laterally operating hinged joint, a supplemental part hinged to said flange engaging part 25 and provided with a longitudinally operating hinged joint, said base plate being bent over the flange and adjustably secured thereto, an L-shaped part rigidly secured to the 30 base plate, a spring interposed between the face of the L-shaped part and the supplemental part and means for holding said spring in place.

7. A signaling apparatus for railroad 35 crossings comprising a plurality of verti-

cally disposed supports and a semaphore, wire supports pivotally mounted on the uprights, vertically disposed rods having their upper ends pivotally secured to the wire supports and their lower ends pivotally secured 40 to a cross arm, a transverse arm rigidly secured to said cross arm and loosely mounted in a socket in the upright, wires extending from the wire supports for operating the signals on the semaphore, and means for 45 rotating said transverse rod whereby the upright rods are alternately raised and lowered, moving the wires to set a desired signal on the semaphore.

8. Apparatus as claimed in claim 7 in 50 which the vertically disposed rods include turn buckles.

9. Apparatus as claimed in claim 7 in which the wires are secured to their supports 55 by tension springs.

10. Apparatus as claimed in claim 7, in which a longitudinally extending wire is provided, having a plurality of downwardly extending flexible supports engaging and supporting the operating wires. 60

11. Apparatus as claimed in claim 7 in which the cross arm and wire supports are provided with a plurality of points to which the vertically disposed rods may be secured, whereby the leverage necessary to operate 65 the wire supports and wires may be increased or diminished.

In testimony whereof I affix my signature.

JAMES W. KENNEDY.
